UNITED STATES PATENT OFFICE

OTTO KÜHNER, OF GÖPPINGEN, GERMANY

SHEET METAL DRAWING PRESS

Application filed September 23, 1931, Serial No. 564,635, and in Germany October 1, 1930.

This invention relates to a sheet-metal drawing press of that type in which, during the drawing of the piece of sheet-metal, or of the blank respectively, that is to say, during that time in which the drawing punch is being moved downwardly and the blank is thereby drawn, the blank is located over a stamp and is held fast thereon between a member (drawing ring or drawing stamp) moved by said punch and a holding ring or an equivalent holding member; and in which, simultaneously therewith, the respective holding member is moved counter to the resistance presented by a pad (preferably a compressed-air pad) which moves that holding member later on into its initial position when the said punch is again being moved upwardly.

There exists with such presses the detrimental possibility that, owing to the movable parts of said pad (in the following termed "drawing device") quickly following the rising punch under the action of the compressed air or other counter-acting medium, the drawing tool is subjected to detrimental blows, or that other drawbacks ensue.

In order to obviate said blows or other drawbacks it has already been proposed to provide a piston in a separate cylinder filled with a liquid and affixed to the lower part of the press table frame, the piston rod being secured to the movable part of the drawing device and being thus moved upwardly and downwardly together with the same. The liquid present above said piston and the liquid present below the same communicate with one another through a pipe provided with a valve controlled by the main shaft of the press in such a manner that it is closed at the end of the downward movement of the movable parts of the drawing device and of the hydraulic piston whereby the flow or circulation of the liquid caused, prior thereto, by the downward movement of the piston is interrupted and whereby, in consequence thereof, is prevented that the movable drawing device members follow instantly the rising punch when this thereafter is again moved upwardly. Some time thereafter the valve is again opened by the control means pertaining thereto so that the ensuing movement

mentioned can now take place without any drawback.

The object of the invention is to attain the same effect without the use of the separate hydraulic cylinder with its piston, that is to say, to present a by far simpler device. This is attained, according to this invention, by arranging the hydraulic locking cushion directly in the casing of the drawing device whereby the existing casing of said cushion may be utilized for housing the locking liquid, and the existing pressing piston, or one of the existing pressing pistons of the drawing device, may be utilized for acting upon said locking liquid. This is effected, on principle, in such a manner that the casing part receiving and containing the locking liquid is connected up by means of a shutting-off valve or the like controlled, for instance, from the main shaft of the press to a pipe leading to a collecting receptacle for the pressure liquid, and that now the piston which acts on the locking liquid, or the casing part enclosing this piston, acts in such a manner that when the movable drawing device members are moved downwardly the locking liquid is sucked in, but cannot, after said downward movement has been finished and the shutting-off valve is closed, escape whereby the movable parts of the drawing device are prevented from again being moved upwardly until the locking has been released by opening the said shutting-off valve.

The invention is illustrated diagrammatically and by way of example on the accompanying drawings on which Figure 1 is a complete front-view, partly in vertical section, of a single-acting sheet-metal drawing press designed according to this invention. Figure 2 is a similar representation showing the lower half of a multiple press, the upper half being left away as unnecessary; and Figure 3 is a side-view of the upper part of Fig. 1, seen from the left.

In Fig. 1, *a* denotes the drawing punch which reciprocates vertically by means of guide members *b* and *c* in the lateral standards *d* of the press, and is actuated from the crank shaft *f* of the same by means of a connecting rod *e*. To the lower end of said

punch is attached the drawing ring *g* which when the punch is moved downwardly draws the blank over the stationary drawing die or stamp *m* by means of the blank holding ring *i*. The drawing die *m* is affixed to the table *k* of the press. The holding ring *i* which embraces the die *m* is vertically shiftable thereon and rests upon vertical rods *n* which are loosely slidable in the die *m*, these rods being supported on a press plate *o* resting in turn upon press rods *p* supported on a cylinder *q*. This latter is located upon a piston *r* along which it can be reciprocated vertically and which is secured to the table of the press by means of a piston rod *s*. This rod has a transverse bore *t* and a longitudinal bore *u*, the lower end of which is in communication with a vessel *w* containing compressed air or another suitable fluid under pressure. The drawing punch is shown in its highest position. In this position of the punch the compressed air presses the cylinder *q* upwardly until it contacts with the bottom surface of the table, and at the end of this movement the cylinder *q* holds the blank holding ring *i* likewise in its uppermost position by means of the members *p*, *o* and *n*, said ring lying in this position in one plane with the upper rim of the drawing die. The crank shaft *f* is driven from the shaft *x* by means of an encased cog-wheel gearing *y*.

The space below the piston *r* communicates with an oil receptacle *3* by the intermediary of a valve *1* opening in the direction to the interior of the cylinder, and a flexible pipe *2*; the oil fills the receptacle *3* only partly, and above it is air either of atmospheric pressure or of a slightly higher pressure. A flexible pipe *4* also extending from the oil space of the receptacle *3* and connected at its other end with the cylinder space below the piston *r* is provided with a valve *5* that is controlled by means of a curved guide groove *10*, *10'* in a fly-wheel *11* on the shaft *f'*, a roll *9* engaging said groove, a bell-crank lever *8*, *8'* which is supported on a pivot *7* and to the arm *8'* of which said roll is attached, and a rod *6* connecting the lever arm *8* with the said valve *(5)*.

The manner of operation of the device is as follows:

When the parts *e*, *a*, *g*, *i*, *n*, *o* and *p* are moving downwardly, they take with them the cylinder *q* that constitutes, together with the piston *r*, the compressed-air cushion or the cushioning device proper respectively, the compressed air present above the piston being now displaced back into the air vessel *w* through the bores *t* and *u* and the pipe *v*. The sheet-metal *h* is, thus, being drawn over the die *m* counter to the pressure of the compressed air, this pressure being that requisite for holding yieldingly fast the rim of the blank *h* between the drawing ring *g* and the holding ring *i*. At the same time oil is sucked

into the space below the piston through the flexible pipe *2* and the now open valve *1*.

When then the drawing punch is again moved upwardly, the cylinder *q* tends to follow it quickly and in a jerky manner under the action of the compressed air whereby the drawing tools *i* and *g* might possibly be injured. Such a detrimental consequence is, however, prevented by the opposing action of the liquid previously sucked into the space below the piston and retained therein, as the valve *1* is now automatically closed and the valve *5* is still closed at the commencement of the upward movement of the drawing punch while the roll *9* is moving in the portion *10'* of the guide groove *10*, *10'*. Only after the drawing punch has been moved upwardly for a certain length of way and the roll *9* has entered into the portion *10'* of the guide groove, the rod *6* is lowered whereby the valve *5* is opened and the pressure in the space above the piston *r* (the compressed air streaming back into this space from the receptacle *w*) is able to move the cylinder *q* upwardly, in that the liquid present below the piston is driven back through the pipe *4* into the oil receptacle *3*. The members *p*, *o*, *n* and *i* follow the upward movement of the drawing punch without any possibility for this latter to strike against the drawing ring, and the roll *9* enters into the portion *10* of the guide groove whereby the valve *5* is closed by the members provided for this purpose, as described.

In the modified sheet-metal drawing press shown in Fig. 2 the drawing die *m* is affixed to the drawing punch *a* and reciprocates, thus, together with it, whereas the drawing ring *g* is firmly secured to the table *k* of the press. The blank holding member *i* is an equivalent for the blank holding ring *i* of Fig. 1; it is also in the present modified case supported from below by a compressed-air cushioning device. The supporting members are formed by bolts *n*, a pressing plate *o* and piston rods *s* which are reciprocated vertically in cylinders *q* suspended from the lower portion of the foot of the press by means of a girder *q¹* and rods *q²*. Each of the piston rods is provided with two pistons *r* which reciprocate in cylinder chambers that are separated from one another by a partition wall *q³*.

The air vessel *w* communicates through a pipe *v* and bores *u* of the piston rods with the cylinder spaces below the pistons *r*. The space *C1* above the upper piston *r* of the middle cylinder communicates with the receptacle *3* containing the locking liquid through a valve *1* and a pipe *2*, as well as through a pipe *4* which is also provided with a valve *5* controlled from the crank-shaft of the press practically in the same manner as has been described with respect to Fig. 1.

B1 denotes a rigid (not yieldingly or elas-

tically supported) blank holder which is attached to the blank holding ram B2 and is also in known manner reciprocated vertically, just as the drawing ram that is guided 5 in it. *h* denotes the skelp or blank.

The manner of operation of this constructional form of the press is as follows:

When the drawing punch *a* and the blank holding ram B2 are moved downwardly, the 10 blank holder B1 holds the blank *h* fast upon the drawing ring *g*, and now the drawing die *m* commences to draw the piece of sheet-metal through said ring, the holder *i* which is subjected to the action of the cushioning 15 device serving as holding-on member. While together with the holder or holding-on member *i* the pistons *r* are moved downwardly, locking liquid is sucked into the space C1 above the piston *r* of the middle cylinder, that 20 liquid preventing, when the drawing ram is again moved upwardly and the valve 5 has been closed, the piston rods *s* from following immediately that upward movement. If the piston rods were able to do that, the blank 25 *h* which (with the constructional form of the press now dealt with) is still held fast by the blank holding member B1 at the time of the commencement of the upward movement of the drawing ram, were subjected to the risk 30 of being destroyed.

The valve 1 and the pipe 2 (Figs. 1 and 2) may, under circumstances, be dispensed with.

I claim:

1. In a sheet-metal drawing press, a cushioning device for the blank holder, comprising a piston and a cylinder closed at both ends and enclosing said piston, said piston and cylinder being one fixed and the other movable and means connecting the movable one of 40 these members operatively with said blank holder; a source of fluid under pressure, a duct connecting one of the spaces in said cylinder with said source of a fluid under pressure; a receptacle containing a liquid; a 45 duct connecting said liquid receptacle and the other space of the said cylinder; and a controlled valve in said liquid duct.

2. In a sheet-metal drawing press, a cushioning device for the blank holder, comprising 50 a stationary piston and a movable cylinder enclosing said piston, closed at both ends and being operatively connected with said blank holder; a source of fluid under pressure, a duct connecting the space above said piston 55 with said source of fluid under pressure; a receptacle containing a liquid, a duct connecting said liquid receptacle and the space below the said piston; and a controlled valve in said liquid duct.

60 3. In a sheet-metal drawing press, a cushioning device for the blank holder, comprising 65 a stationary cylinder closed at both ends and a piston movable in said cylinder and being operatively connected with said blank holder; a source of fluid under pressure, a

duct connecting the space below the piston with said source of fluid under pressure; a receptacle containing a liquid; a duct between 70 said liquid receptacle and the space above the said piston, and a controlled valve in said liquid duct.

4. In a sheet-metal drawing press, a cushioning device for the blank holder, comprising 75 a piston and a cylinder closed at both ends, enclosing said piston, and means connecting one of these members operatively with said blank holder; a source of fluid under pressure, a duct establishing communication between one of the spaces in said cylinder and said source of fluid under pressure; a receptacle containing a liquid; a duct establishing communication between said receptacle and the other space of the said cylinder; a valve in said duct; a cam disk driven by 80 the press, and means for transmitting motion from the cam of said disk to said valve so as to control it thereby.

5. In a sheet-metal drawing press, a cushioning device for the blank holder, comprising 85 a piston and a cylinder, closed at both ends, enclosing said piston, and means connecting one of these members operatively with said blank holder; a source of fluid under pressure, a duct establishing communication between one of the spaces in said cylinder and said source of fluid under pressure; a receptacle containing a liquid; a duct establishing communication between said receptacle and the other space of the said cylinder; a valve in said last named duct; a disk 90 driven by the press and having a lateral groove consisting of two portions of different radii; a roll running in said groove; a double-armed lever, to one arm of which said roll is attached; and a connection between the 95 other arm of said lever and said valve.

In testimony whereof I affix my signature.

OTTO KÜHNER.
